WARMER FOR FOOD PRODUCTS

Harold J. Fitzgerald, Whitefish Bay, Wis., assignor to Supurdisplay, Inc., Milwaukee, Wis., a corporation of Wisconsin

Application February 27, 1957, Serial No. 45,021

Term of patent 14 years

(Cl. D81—10)

Fig. 1.

Fig. 2.

Fig. 3.

Fig. 1 is a view in perspective of a warmer for food products, showing my new design.

Fig. 2 is a front view in elevation of the warmer for food products shown in Fig. 1, and

Fig. 3 is a side view in elevation of the warmer for food products.

The sloping rear panel of the hood member is plain.

I claim:

The ornamental design for a warmer for food products, as shown and described.
